UNITED STATES PATENT OFFICE.

ROBERT C. LANDERS, OF LEBANON, KANSAS.

FAN ATTACHMENT FOR SEWING-MACHINES.

1,027,259.

Specification of Letters Patent. Patented May 21, 1912.

Application filed November 29, 1911. Serial No. 663,006.

To all whom it may concern:

Be it known that I, ROBERT C. LANDERS, a citizen of the United States, residing at Lebanon, in the county of Smith and State of Kansas, have invented new and useful Improvements in Fan Attachments for Sewing-Machines, of which the following is a specification.

This invention relates to fan attachments for sewing machines, and has for an object to provide an attachment of this kind which can be readily applied to the usual hand wheel upon the needle bar shaft of the machine to be operated thereby and thus create a circulation of air which will be found most advantageous where machines are used in factories or like places.

Another object of the invention is to provide a fan attachment that can be readily attached to the stop motion screw in the center of the hand wheel, without necessitating changes in the construction of the screw.

In the drawing, forming a portion of this specification and in which like numerals of reference indicate similar parts in the several views:—Figure 1 is a side view of a portion of a sewing machine showing my improved fan attachment applied to the hand wheel thereof. Fig. 2 is a side view 30 of the fan detached from the machine. Fig. 3 is a section on an enlarged scale through a portion of the wheel showing the manner of connecting the hub of the fan thereto.

The sewing machine 1 herein shown is of a construction wherein the hand wheel 2 is mounted in the usual manner to the needle bar shaft, the latter including the stop motion screw 3.

The fan attachment comprises an outer rim 4 and an inner collar 5. These parts 4 and 5 are arranged in concentric relation relatively and the inner collar is of a size which will snugly receive the head of the screw 3, as shown in Fig. 3 of the drawing. Suitable vanes or blades 6 connect the rim 4 with the collar 5 and they may be secured thereto in any suitable obvious manner, preferably through the use of solder. The rim 4 is preferably provided with slots 7 through 50 which the outer ends of the blades or vanes 6 are extended. By extending the outer

ends of the blades through the slots the blades will be confined against bending from their original planes. The collar 5 is provided at its opposite sides with flexible ears 55 8 which are designed to be bent down against the opposite sides of the head of the screw 3, whereby the fan can be immovably mounted upon the wheel 2 so as to rotate with the latter as will be understood.

From the construction described it is obvious that the fan provides means whereby when the wheel 2 is rotated the air disturbed thereby will circulate freely in the direction of the operator of the machine. 65 The fan is of a comparatively simple construction, it may be manufactured at a minimum cost and applied to machines of standard construction without necessitating alterations to any parts thereof.

In the modified form of the invention shown in Fig. 4, the fan includes a rim 10 and a collar 11. The collar is provided with radial sockets 12 and the blades or vanes 13 are provided with reduced inner ends 14 75 which are loosely fitted in the sockets. The outer ends of the blades or vanes are soldered or otherwise fixedly secured to the rim 10. From this construction it will be seen that the band 11 can be readily removed from 80 the vanes or blades of the fan so as to permit a band of any required internal diameter to be associated therewith and thereby permit the fan to be adjusted to stop-motion screws of different sizes or configura- 85

I claim:

1. A fan attachment for sewing machines comprising a rim provided with radially arranged slots, a collar disposed in concentric relation with the rim, and adapted for engagement with the stop-motion screw of the hand wheel of a machine, blades connecting the collar with the rim, and means on the opposite peripheral edges of the collar adapted for clamping engagement with the opposite side faces of the screw so as to hold the wheel immovably mounted thereon.

2. A fan attachment for sewing machines comprising a rim provided with radially arranged slots, a collar disposed in concentric relation with the rim and adapted for en-

gagement with the stop-motion screw of the hand wheel of a machine, blades connecting the collar to the rim, and tongues formed on the opposite peripheral edges of the collar and adapted to be bent into engagement with the opposite side faces of the screw to hold the fan immovably mounted thereon.

In testimony whereof I affix my signature in presence of two witnesses.

ROBERT C. LANDERS.

Witnesses:

JOSEPH PURSIFULL,
PERCY R. ATKINS.
